4 Claims. (Cl. 175—45)

This invention relates to drilling apparatus and particularly to apparatus for deflecting or changing the direction of a hole when drilling same.

This application is a continuation-in-part of our prior copending application filed October 14, 1957 bearing Serial No. 689,871 for "Drilling Deflection Method and Apparatus," now abandoned.

In the drilling of oil wells and in the drilling of other holes in the ground, it often becomes necessary or desirable to drill the hole or well in a direction different than it has been previously drilled. The change in the direction of the hole is known in the field as the deflection of the hole, and under present practice, the deflection of the hole is accomplished by first setting a whipstock in the hole, then lowering a pilot bit for making an initial pilot hole known as a "rat hole" at the desired angle of deflection from the previously drilled hole, and thereafter the pilot bit is retracted and a full size reamer bit is lowered for enlarging the diameter of the deflected hole to substantially the same size as the previously drilled hole.

As can be appreciated, the number of "runs" or "trips" for accomplishing the above described sequence of operations involves a considerable amount of lost time during the raising and lowering operations. Furthermore, the number of runs are frequently greatly multiplied because if the hole is to be deflected more than about three and one-half degrees from the direction of the previously drilled hole, it is necessary to obtain a direction indication of the first leg of the deflected hole with a special indicating tool of any one of several known constructions and then the above described sequence of steps is repeated to drill the second leg of the deflected hole at an angle of deflection with respect to the first leg.

It is an object of this invention to provide a new and improved apparatus for drilling holes at an angle of deflection from a previously drilled hole without requiring the use of a whipstock for guiding the drill bit at the desired angle of deflection.

Another object of this invention is to provide a new and improved apparatus for drilling holes at an angle of deflection from a previously drilled hole which includes the drilling of a pilot hole or rat hole followed by the reaming of same in an enlarged diameter without removing the apparatus from the hole.

An important object of this invention is to provide a new and improved apparatus for drilling holes at an angle of deflection wherein the angle of deflection is selected prior to lowering the apparatus into the well or other hole, and wherein such angle may be varied within limits for obtaining different amounts of deflection in the drilled hole.

A further object of this invention is to provide a new and improved apparatus for drilling a well or hole at an angle of deflection wherein the direction of such deflection may be determined with known deflection indicators, and wherein the apparatus may be manipulated in the well or hole to change the direction of deflection if desired.

A particular object of this invention is to provide a new and improved apparatus for drilling a well or hole which includes a pilot bit for drilling a pilot or rat hole, and a reamer which is positioned above the pilot bit during the drilling of the pilot hole or rat hole but which is adapted to telescope over the pilot bit for reaming the

2

pilot hole or rat hole to an enlarged size without withdrawing the apparatus from the well.

Still another object of this invention is to provide a drilling apparatus for drilling deflected holes and the like wherein a pilot bit and a reamer are provided and wherein means is included for telescoping and extending the pilot bit with respect to the reamer by manipulation of the pipe string supporting the apparatus, whereby the apparatus may be manipulated from the ground level to select either the pilot bit or the reamer for operation down in the hole.

The preferred embodiment of this invention will be described hereinafter together with other features thereof and additional objects will become evident from such description.

The invention will be more readily understood from a reading of the following specification and by reference to the accompanying drawings forming a part thereof wherein an example of the invention is shown, and wherein:

FIG. 1 is an elevation of the lower portion of the apparatus of this invention to show the pilot bit in the position it assumes in a previously drilled hole or well just prior to the drilling of the deflected hole therebelow;

FIG. 2 is a view, partly in elevation and partly in section, illustrating the apparatus of this invention in the position such apparatus assumes after the pilot bit thereof has drilled the pilot hole or rat hole at a deflected angle with respect to the previously drilled hole;

FIG. 3 is a view, partly in elevation and partly in section, illustrating the apparatus of this invention with the pilot bit retracted for subsequent reaming of the pilot hole or rat hole with the reamer of the apparatus so as to enlarge the pilot hole or rat hole to the desired diameter;

FIG. 4 is a view, partly in elevation and partly in section, illustrating the central portion of the apparatus of this invention in detail;

FIG. 5 is a horizontal sectional view taken on line 5—5 of FIG. 4;

FIG. 6 is a horizontal sectional view taken on line 6—6 of FIG. 4; and

FIG. 7 is a view similar to FIG. 2 and shows an additional modification of the present invention.

In the drawings, the letter A designates generally the apparatus of this invention which is so constructed that it is adapted to be lowered into a previously drilled hole such as a well bore W (FIGS. 1, 2, and 3) for initially drilling a pilot hole or rat hole H (FIGS. 2 and 3) and for subsequently reaming the hole H to an enlarged diameter without removing the apparatus A from the well bore W.

The apparatus A includes a housing 10 at its upper end which is formed with suitable threads 10a for connection with corresponding threads 11 on the lower end of a section of drill pipe P, a portion of which is illustrated in FIGS. 2 and 3. The drill pipe P will be understood to extend to the ground level or surface of the well and it is used for the lowering, raising, and other manipulation of the apparatus A of this invention, as will be explained in detail hereinafter. The housing 10 has a fluid passage opening 10b below the threads 11 of the drill pipe P for establishing fluid communication from the bore of the drill pipe P into the bore or internal opening 10c of the housing 10.

The lower end of the housing 10 has internal threads 10d for receiving external threads 12a formed on the upper portion of a reamer 12. The reamer 12 is annular and has an internal bore 12b which is tapered to an upper cylindrical portion which corresponds in diameter with the internal bore 10c of the housing 10 in the preferred form of the invention so that the lower end of the

housing 10 is open at the reamer 12 as illustrated in FIG. 2 in particular. The reamer 12 is formed with suitable reaming teeth 12c which are best seen in FIG. 3 of the drawings, and such teeth 12c are utilized for enlarging the diameter of the pilot hole or rat hole H, as will be explained hereinafter.

One or more J-slots or other shaped slots 14, preferably two in number, are formed in the bore 10c of the housing 10. Each of the slots 14 is formed with an upper lateral offset 14a and a lower lateral offset 14b. The lateral offset 14b connects the main portion of the slot 14 with a vertical offset 14c.

A pilot bit or other type of drill bit B is connected with the housing 10 through a shank assembly S which extends from the bit B upwardly into the interior of the housing 10, as will be explained. The shaft or shank assembly S includes an upper shaft section S-1 and a lower section S-2 therebelow. The upper section S-1 extends from the interior of the housing 10 and is pivotally connected with the lower section S-2 which is directly connected with the bit B, as will be explained.

The upper shaft or shank section S-1 includes a tubular guide body 20 (FIGS. 2 and 4) which has one or more guide pins 21 mounted or formed therewith. There is a pin 21 for each slot 14 so that each slot 14 has a guide pin 21 movable therein in accordance with the manipulation of the housing 10 relative to the shaft or shank assembly S, as will be evident hereinafter. The guide body 20 has an internal bore 20a therethrough for fluid passage, but on the external surface of the body 20, a plurality of annular grooves 20b are provided for receiving O-rings 23 which provide a fluid seal between the external surface of the body 20 and the internal surface of the housing 10. At the upper end of the body 20, a recess 20c is provided for receiving a support ring 25 which has a bore 25a therethrough of substantially the same size as the bore 20a. The ring 25 has a blade 26 mounted therein which has a short knife edge 27 and a long knife edge 28 formed therewith. Therefore, to change the position of the blade 26 the ring 25 is moved relative to the body 20. As will be more evident hereinafter, the position of the blade 26 serves as an indication of the direction in which the bit B is positioned with respect to the housing 10, and therefore, when the blade 26 is positioned for indicating the direction of inclination of the bit B with respect to the housing 10, a set screw 29 is threaded into contact with the ring 25 and is locked there in position with a lock nut 30 or other suitable lock means. Thereafter, a conventional directional indicating tool, preferably of the type having a lead plate, may be used by lowering same down through the drill pipe P and into contact with the knife edges 27 and 28 so that the plate of the indicator member which contacts the edges 27 and 28 receives an impression or indication of the edges 27 and 28. Such indication therefore is an indication to the operator at the surface or ground level that the bit B is extending in a particular direction with respect to the housing 10. It will be understood of course that other types of indicator means that the knife edges 27 and 28 could be utilized with the invention without departing from the scope of this invention.

Below the body 20, a tubular adaptor 35 is provided. Such adaptor 35 may be connected in any desired manner to the body 20, but as illustrated internal threads 35a on the adaptor are in threaded engagement with external threads 20d on the lower portion of the body 20. It will be observed that threads 35a and 20d are preferably tool joint threads. The adaptor 35 has an internal bore 35b which is of substantially the same diameter as the bore 20a of the body 20. The adaptor 35 has an annular groove or a plurality of recesses 35c formed for receiving springs 36 or a single coil spring

for a purpose to be hereinafter described. The adaptor 35 has a reduced external diameter at its lower end which is threaded at 35d and is in threaded engagement with threads 38a on a pivot head 38 so that the adaptor 35 is directly connected to the pivot head 38. It will be recognized that other means for connecting the adaptor 35 to the head 38 could be utilized without departing from the invention. The upper part of the bore 38b of the pivot head 38 is of substantially the same diameter as the main bore portion 35e, but a portion of bore 38b is arcuate and extends inwardly with respect to the bore 38b as shown in the drawings to provide a curved seat 38c. The curved seat 38c merges with a downwardly and outwardly inclined inner bore wall 38d. The inclination of the wall 38d is sufficient to permit the position of the pilot bit B at an angle with respect to the longitudinal axis of the housing 10. Normally, the bit B will not extend at an angle greater than about three and one-half degrees from the vertical axis of the housing 10 and therefore the inclination of the inclined surface 38d ordinarily does not have to be greater than about three and one-half degrees with respect to the vertical axis of the housing 10, but it of course could be larger than that if so desired, and conceivably, the inclination could even be less than three and one-half degrees under some circumstances.

The lower shank section S-2 includes a tubular member 40 which is formed with a pivot head or ball 41 at its upper end. The pivot head or ball 41 is preferably integral with the tubular member 40 and the bore 40a of the tubular member 40 is preferably of substantially the same diameter as the bore 41a through the ball 41. The ball 41 is maintained in contact with the curved seat 38c by means of a floating pusher ring 42 which is urged downwardly into contact with the ball 41 by the springs 36. The bore 42a of the pusher member 42 is preferably substantially the same diameter as the bore 41a of the pivot head or ball 41. The lower surface 42b of the pusher member 42 is curved to conform with the external ball shape of the head or ball 41 so that relative movement can occur therebetween. The ball 41 is prevented from turning or rotating relative to the member 38 by means of retaining pins 45 which are threaded or otherwise connected to the member 38 and extend into longitudinal slots 41b formed in the ball 41. The pins 45 do not extend into the slots 41b sufficiently to prevent a lateral pivotal movement of the ball 41 on the seat 38c. Therefore, the tubular member 40 can move from the position shown in FIG. 4 to the position shown in FIG. 2 without interference from the pins 45. In fact, the tubular member 40 can move from contact with one side of the wall 38d to the other side thereof so as to obtain such limited pivotal movement, but relative rotation between the member 40 and the member 38 is prevented by the pins 45.

In order to maintain the tubular member 40 at a desired angle with respect to the longitudinal axis of the housing 10 and the head 38, a cam ring 46 is slidably mounted on the member 40. Such cam ring 46 has an upper surface 46a which is adapted to contact the lower end 38e of the head or member 38. The surface 46a of the cam ring 46 is inclined so that when it is in contact with the surface 38e, the tubular member 40 is caused to be moved or positioned at an angle with respect to the longitudinal axis of the housing 10. This position is seen in FIG. 2 of the drawings. A spring or resilient means 47 acts against the lower surface of the cam ring 46 to maintain the ring 46 with its surface 46a in contact with the surface 38e, but lateral shifting of the ring 46 with respect to the member 38 is not prevented so that the tubular member 40 may move to the position shown in FIG. 4 from the position shown in FIG. 2 by simply compressing the spring 47 and such action actually occurs during the drilling operation with the bit B, as will be more fully explained. The cam

ring 46 is held against rotation with respect to the tubular member 40 by any suitable means such as keys or splines 40b which engage in coacting keyways or splines 46b in the cam ring 46 so that the cam ring 46 may slide upwardly and downwardly on the member 40 without turning relative thereto.

The lower end of the tubular member 40 is provided with external threads 40c for receiving a retaining nut 48 for the spring 47 and a lock nut 49 for holding the nut 48 in a desired position to obtain sufficient compression of the spring 47 on the cam ring 46 to maintain the ring 46 with its surface 46a in contact with the surface 38e.

The lower shank section S-2 also includes a relatively heavy sleeve 55 which has a central passage 55a therethrough. Such sleeve 55 is in the nature of a drill collar or collars used in drilling and it preferably has internal tool joint threads 55b at its upper end for threaded engagement with a threaded connector plug 56 (FIGS. 2 and 4) which is threaded onto the lower end of the tubular member 40. The plug 56 has a central passage therethrough so that fluid communication from the bore 40a of the tubular member 40 is continued on through to the bore 55a of the sleeve or drill collar 55. The lower end of the sleeve or drill collar 55 is formed with internal threads 55c which are adapted to receive the external threads on the bit B. The bit B is formed with water or mud passages 58 so that the mud or other drilling fluid may flow all of the way from the drill pipe P through the apparatus of this invention for discharge at the openings 58 of the bit B to facilitate drilling. The invention is of course not limited to the particular type or shape of the drill bit B illustrated in the drawings because various known types of drill bits may serve in place of the bit B illustrated.

In the use or operation of the apparatus of this invention, the apparatus of this invention is positioned with the shank section S-2 at an angle with respect to the longitudinal axis of the housing 10 as shown in FIG. 2 and then the apparatus is lowered on the drill pipe P until the bit B hits the bottom W' as shown in FIG. 1 of the drawings. The amount of the deflection of the shank section S-2 with respect to the longitudinal axis of the housing 10 is determined by the inclination of the inclined surface 46a on the cam ring 46, within the limits provided by the downwardly and outwardly inclined surface 38d. The cam 46 may of course be changed so as to obtain a different angle of deflection of the bit B with respect to the housing 10 if so desired, but in most instances, the inclination of the surface 46a with respect to the surface 38e will be such that the shank section S-2 will be at approximately three and one-half degrees with respect to the longitudinal axis of the housing 10 so that the hole H which is drilled with the bit B is at approximately three and one-half degrees deflection with respect to the vertical axis of the well bore or hole W which has been previously drilled with another bit. The pins 21 on the body 20 of the upper shank section S-1 are positioned in the vertical offset 14c of each of the slots 14 as the apparatus is lowered into the well bore W to the bottom W' thereof. Therefore, the shank assembly S is prevented from telescoping within the bore 10c of the housing 10 during the lowering of the apparatus A of this invention into the well bore W.

When the bit B has reached the lower portion or bottom W' of the well bore W which has previously been drilled with another bit, rotation is imparted to the bit B by a rotation of the drill pipe P from the ground level or surface of the well. Such rotation is in the right-hand or clockwise direction as viewed from the top of the apparatus so that the pins 21 remain in the vertical offset portions 14c of the guide slots 14 for transmitting the rotation of the drill pipe P through the housing 10 to the shaft or shank assembly S and ultimately to the pilot or drill bit B. As the drilling of the hole H progresses,

5

the drill bit B remains in its deflected direction which was initiated by the location of the shank section S-2 at an angle with respect to longitudinal axis of the housing 10 and the shank section S-1 tends to move laterally so that for each one-half revolution of the drill pipe P and the apparatus A, the ring 46 moves from the position shown in FIG. 2 to the position shown in FIG. 4. Actually, the tubular member 40 will remain at the inclination shown in FIG. 2 rather than vertical as shown in FIG. 4 but the space between the inclined surface 46a on the cam ring 46 and the lower edge 38e of the head member 38 will occur for each half revolution because the upper portion of the apparatus A will tend to shift laterally relative to the bit B. Therefore, the bit B continues to move in the deflected direction in which it is initially positioned as the bit B is rotated and therefore the bit B cuts the pilot bit hole or rat hole H. The drilling can continue to the depth desired and when the reamer 12 reaches the bottom W' of the previously drill hole W, then the reamer 12 begins to enlarge or ream out the hole H to an increased diameter. Thus, as the bit B continues to drill the pilot hole, the reamer 12 follows to ream out the hole H to an enlarged diameter.

When it is desired to ream the hole H to the bottom thereof, or substantially the bottom thereof, the apparatus A is lifted sufficiently to position the lower part of the drill bit B on the bottom surface W' which remains as a shelf at the upper end of the hole H (FIG. 3). The bit B is thus supported on the bottom W' of the previously drilled hole W and the drill pipe P is turned to the left so as to move the housing H relative to the pins 21 for moving the pins 21 into the lateral offset portions 14b and then into the bottom of the slot 14. Thereafter, the housing 10 is telescoped over the shank assembly S and the pins 21 are guided in the longitudinal portions of the slots 14 until they reach the upper end thereof. Then, upon applying a right-hand rotation to the housing 10, the pins 21 are positioned in the lateral offsets 14a at the upper ends of the slots 14.

It should be noted when the shaft assembly S is telescoped within the bore 10c of the housing 10, the lower shank section S-2 is caused to straighten out as shown in FIG. 4 of the drawings when the lower shank section S-2 reaches the point of entry into the housing 10 due to the fact that the cam 46 can move downwardly to the position shown in FIG. 4 against the action of the spring 47 when the member 56 engages the tapered bore 12b.

With the bit B substantially retracted as shown in FIG. 3, the reamer 12 is then utilized for fully enlarging the diameter or size of the hole H to substantially the same diameter as the previously drilled hole W. The bit B preferably extends below the reamer H a slight amount so that if desired, the bit B may be again raised and positioned on the bottom W' of the previously drilled hole W for turning the housing 10 to the left and raising same to again locate the pins 21 to the vertical offset 14c for further offset drilling without requiring the removal of the apparatus A from the previously drilled hole W. For example, after the hole H has been drilled and has been reamed with the reamer 12, the direction of the deflection can be determined from the ground level by the lowering of a known type of deflection direction indicator into contact with the knife edges 27 and 28. When the direction of the hole H has been determined, and the hole H has been drilled to a sufficient depth and has been reamed with the reamer 12, it may be desirable to make a further deflection in the hole H below the portion of the hole H which has then been drilled and reamed. If such is desired, the bit B may be extended again and the pins 21 may be locked in the vertical off-set portions 14c of the slots 14 and further deflection from the reamed hole H may be obtained. Also, if the deflection direction is not proper, such direction may be changed by beginning the drilling of the additional or new hole at different direction. Therefore, successive legs of deflected hole may be

75

drilled at different angles and different directions with respect to the axis of the previously drilled hole W and with respect to each leg which is thereafter drilled with the pilot bit B and which is reamed with the reamer 12 so that all of such operations can be conducted without removing the apparatus A of this invention from the hole W. It can therefore be seen that the apparatus of this invention eliminates the many return trips or runs required with conventional whipstock equipment for obtaining the deflection in a well bore or hole. Also, it will be evident that the device of this invention eliminates the use of a whipstock for obtaining a deflected hole. Other advantages are also believed evident from the foregoing description.

In FIG. 7, a slight modification of the invention is provided. In the form of the invention shown in FIG. 2, well fluid circulated downwardly through pipe P will aid in extending shaft assembly S after the housing 10 has been turned to the left as described in the above paragraph.

In order to fully utilize the effect of the drilling fluid circulated through pipe P, a hollow shaft or pipe 100 is connected into the body 20 as shown in FIG. 7. The shaft is provided with a fluid conducting passage 101 which communicates with bore 20a, and at the upper end of shaft 100, there is arranged a piston 102. The piston 102 is provided with seals 103 for sealably engaging the well of housing 10 to prevent fluid circulation around the piston.

In the form of the invention shown in FIG. 7, the housing 10 will be extended to accommodate the shaft 100 and piston 102. The upper end of piston 102 is provided with a recess 20c' which is similar to recess 20c in FIG. 4.

When the form of invention shown in FIG. 7 is used, the knife edges 27' and 28' must be moved to the top of the piston. Thus, recess 20c' is provided in the top of piston 102 and is similar to recess 20c. Also, a support ring 25' is provided in recess 20c' and is shown schematically in FIG. 7. The support ring 25' has a bore therethrough the same size as bore 101 in shaft 100. The ring 25' supports the blade 26' which has a short knife edge 27' and a long knife edge 28'. The function of the blade 26' and edges 27' and 28' is the same as described with regard to the form of the invention shown in FIGS. 1-6, inclusive. The ring 25' and knife blade 26' may be arranged in the top of piston 102.

Also, the function, construction, and operation of the tool shown in FIG. 7 is the same as described with regard to FIGS. 1-6, inclusive, of the drawings. In the form of the invention shown in FIG. 7, the piston 102 will positively push or urge the shaft assembly S from housing 10 when housing 10 has been turned to the left so as to cause pins 21 to move down guide slots 14.

The foregoing disclosure and description of the invention is illustrative and explanatory thereof and various

changes in the size, shape, and materials as well as in the details of the illustrated construction may be made within the scope of the appended claims without departing from the spirit of the invention.

5 What is claimed is:

1. An apparatus adapted to be mounted on a drill pipe for drilling a hole at an angle of deflection comprising:

- (a) a tubular housing having means at its upper end for connection to a drill pipe,
- (b) an annular reamer mounted on the lower end of said housing for rotation therewith,
- (c) a pilot bit body slidably mounted in said housing,
- (d) a pilot bit connected at the lower end of said body,
- (e) connector means between said housing and said body for slidably connecting said pilot bit body to said housing for permitting telescoping and extending of said pilot bit relative to said reamer,
- (f) said connector means including means for holding said pilot bit body in said housing and holding said pilot bit both in telescoped position and extended position relative to said reamer so that when the pilot bit is extended it drills a pilot hole and when the pilot bit is telescoped the pilot hole is enlarged by the reamer,
- (g) and means connecting said pilot bit to said pilot bit body for positioning said pilot bit at an angle with respect to the longitudinal axis of said reamer when said pilot bit is in an extended position.

2. The structure set forth in claim 1 wherein said connector means includes a substantially J-shaped slot in said housing and a pin connected to said pilot bit body and extending slidably in said slot.

3. The structure set forth in claim 1 including a piston connected to the upper end of said pilot bit body and disposed within said housing in sealing sliding contact therewith so that fluid pressure acting on the piston may move said pilot bit longitudinally relative to said reamer.

4. The structure set forth in claim 1 including marking means on the upper end of said pilot body for marking an impression member lowered into the hole through the drill string to thereby indicate the angular direction of the pilot bit and the deflected hole drilled therewith.
